(57) **CLAIM**

The ornamental design for a cleaning article with surface pattern, as shown and described.

DESCRIPTION

The sole FIGURE is a plan view of the new design for a cleaning article with surface pattern.

The claimed design is represented by the solid lines in the drawing. The broken lines in the drawing represent environmental subject matter that forms no part of the claimed design. The broken lines form no part of the claimed design. The thickness of the cleaning article with surface pattern forms no part of the claimed design.
